UNITED STATES PATENT OFFICE.

ADJUDEUR AUBÉ, OF WOONSOCKET, RHODE ISLAND, ASSIGNOR TO THE DRAPER COMPANY, OF PORTLAND, MAINE, AND HOPEDALE, MASSACHUSETTS.

SHUTTLE FOR LOOMS.

SPECIFICATION forming part of Letters Patent No. 630,793, dated August 8, 1898.

Application filed March 20, 1898. Serial No. 709,818. (No model.)

To all whom it may concern:

Be it known that I, ADJUDEUR AUBÉ, of Woonsocet, county of Providence, State of Rhode Island, have invented an Improvement 5 in Shuttles for Looms, of which the following description, in connection with the accompanying drawings, is a specification, like letters on the drawings representing like parts.

This invention relates more particularly to self-threading shuttles for looms of that type wherein a filling-carrier is automatically supplied to the shuttle whenever for any reason the weft fails to be properly laid in the shed— 10 as, for instance, in United States Patent No. 529,940, dated November 27, 1894, wherein the fresh filling-carrier is inserted in the shuttle at one open side and by its entrance acts to eject from the opposite open side of the shuttle the spent filling-carrier. It has been found in practice that when such looms are run at high speed the tip of the filling-carrier sometimes is deflected to one side as it enters the shuttle, so that the holding means carried 15 by the shuttle does not firmly engage the head of the filling-carrier. More frequently the tip of the ejected filling-carrier will deviate from its proper path and the filling-carrier will twist or move into a position at an 20 angle to the longitudinal axis of the shuttle, interfering with the proper entrance of the fresh filling-carrier or otherwise obstructing the proper operation of the parts.

In my present invention I have overcome 25 the before-stated objectionable features by providing the shuttle with a support or stop for the tip of the filling-carrier when the latter is ejected, to thus always insure the discharge of the filling-carrier head downward, 30 a narrow guideway in the shuttle-body leading to the support to conduct and guide the tip of the incoming filling-carrier, the walls of the guideway preventing lateral deviation of the tip of a filling-carrier when the latter 35 is being ejected from the shuttle. Under normal conditions the tip of the filling-carrier does not contact with the support, but is held a short distance above it.

Figure 1 is a top or plan view of a self-

threading shuttle embodying my invention, 50 with a filling-carrier in place therein, the filling omitted for the sake of clearness. Fig. 2 is a side view thereof, partly broken out to show the tip-support or stop and the guideway leading thereto; and Fig. 3 is a transverse 55 sectional view of the shuttle on the line *x*-*x*, Fig. 1.

The shuttle B, the holder comprising jaws C, notched or grooved at their inner sides to be entered by ribs or projections *d* on the 60 head *d* of the filling-carrier D, shown as a cop-skewer, and the self-threading device T are and may be all of usual or suitable construction.

The shuttle is shown as open at its top and 65 bottom, and at its forward end I form a longitudinal narrow slot or recess *b*, open at its inner end and extending from the top of the shuttle toward its under side, forming a guideway with vertical side walls, leaving a support or stop *b'* at the bottom of the guideway in the plane of the longitudinal axis of the shuttle and at or near its under side. At its upper end or entrance the guideway *b* may be made slightly flaring, as at *b*², to facilitate 70 the entrance of the tip of the filling-carrier D thereinto.

When a full filling-carrier is inserted in the shuttle, its tip enters the narrow guideway *b* and is thereby maintained in proper position 80 to enable the head *d* to accurately enter and be engaged by the holding means C. Should the projections on the head of the incoming filling-carrier fail to register with the grooves in the jaws, then the support or stop *b'* will 85 engage the tip of the filling-carrier and prevent it from descending below the under side of the shuttle.

When a spent filling-carrier is about to be ejected from the shuttle, the tip is held by the 90 support *b'*, so that the head will descend first and at the same time the adjacent side walls of the guideway *b* act to position the tip and prevent its lateral deflection, so that the ejected filling-carrier will pass properly and 95 without catching through the discharge slot or opening in the bottom of the shuttle-box.

The support or stop also serves to prevent

the dropping of the tip of the filling-carrier when the shuttle is in motion should the head become loosened in the holder.

Having fully described my invention, what 5 I claim, and desire to secure by Letters Patent, is—

A shuttle-body having holding-jaws to receive and frictionally engage the head of a removable filling-carrier and permit it to be 10 discharged therefrom at the side opposite that at which it enters the jaws, a support or stop located in such position as to be struck by the tip or delivery end of the filling-carrier

as the latter is ejected from the shuttle, and a narrow, deep guideway leading from the top 15 of the shuttle-body to the support or stop, to direct the tip of the filling-carrier when the latter is moved bodily and prevent lateral deflection thereof.

In testimony whereof I have signed my 20 name to this specification in the presence of two subscribing witnesses.

ADJUDEUR AUBÉ.
